JACK

Quintin G. Noblitt and Earl C. Booth, Indianapolis, Ind., assignors to Noblitt-Sparks Industries, Inc., Columbus, Ind., a corporation of Indiana

Application January 26, 1932. Serial No. 589,005

12 Claims. (Cl. 254—98)

Our invention is concerned with jacks, and particularly with screw jacks of the type in which the screw is held against vertical movement and serves as it rotates to raise or lower a lifting member.

It is the primary object of our invention to produce a jack which lends itself to sheet-metal construction. A further object of our invention is to produce a jack which may be simply and economically manufactured and which will prove sturdy, durable, and efficient in use.

The accompanying drawings illustrate our invention: Fig. 1 is a vertical section through a jack on the line 1—1 of Fig. 3; Fig. 2 is a front elevation of the jack with a part of the hollow standard broken away; Figs. 3 and 4 are horizontal sections respectively on the lines 3—3 and 4—4 of Fig. 1; Fig. 5 is a fragmental side elevation of the jack with a part of the standard broken away; Fig. 6 is a fragmental rear elevation of the jack with parts thereof broken away and illustrated in section; Fig. 7 is a view similar to Fig. 5, but showing a modified construction; Fig. 8 is a perspective view illustrating details of the lifting member and parts associated therewith; and Fig. 9 is a horizontal section on the line 9—9 of Fig. 7.

As is clear from Figs. 1 to 3, the jack embodies a housing comprising a base 12 and an upwardly extending hollow standard formed of two sheet-metal stampings 13 and 14. Each of the stampings 13 and 14 has at its lower end an outwardly directed flange adapted to rest upon the base 12 and to be secured thereto as by riveting or welding. The stampings 13 and 14 are so shaped that the upper part of the standard which they form is generally cylindrical, while the lower part of such standard is conical, flaring outwardly to the point where it meets the base 12. In addition, the stampings 13 and 14 are formed at one side and near the lower ends with aligned grooves of semicircular cross-section which, in the assembled housing, provide a bearing for a pinion 15.

Within the standard formed by the stampings 13 and 14, a hollow lifting member 16 is vertically slidable. The upper end of the member 16 projects upwardly beyond the standard, and is there flared outwardly and provided with grooves in its upper surface to facilitate its engagement with the object which is to be lifted.

For the purpose of moving the lifting member 16 vertically, there is secured to its lower end a nut 18 provided with internal screw threads adapted to co-operate with a screw 19 which extends vertically within the lifting member 16.

The lower end of the screw 19 is secured, as by welding, to a gear 20 which is rotatably mounted in the housing in position to mesh with the pinion 15. The rotatable unit which comprises the screw 19 and gear 20 is provided in its lower face with an axial recess adapted to receive a convex boss on the upper face of a thrust-bearing member 21 that is secured in the base 12 of the jack.

Like the base 12 and the stampings 13 and 14, the lifting member 16 is preferably formed of sheet-metal. The longitudinal edges of the sheet-metal forming the lifting member 16 are bent radially outward and disposed in abutting relation to form a flange 22 which is received in a vertically extending groove in the standard, as is clear from Fig. 3. By this arrangement, the lifting member 16 is prevented from rotating; and by operating the pinion 15 to rotate the gear 20 in one direction or the other, the lifting member 16 may therefore be raised or lowered.

For the purpose of securing the two stampings 13 and 14 together their longitudinal edges are out-turned to provide abutting flanges. These flanges on one of the stampings, here shown as the stamping 13, are wider than the flanges on the other member and are folded thereover, as is clear from Fig. 3, to hold the two stampings together.

Preferably, the lifting member 16 is provided with a lifting surface in addition to that provided in its upper end. For this purpose, the flanges 22 on the lifting member, at a point intermediate its length, extend radially outward to form a step 25. To provide for the projection of the step 25 beyond the limits of the jack-standard, the flanges at the longitudinal edges of the stampings 13 and 14 on the front of the housing are cut away to leave a slot 26 in which the step 25 slides as the lifting member 16 is raised and lowered.

Preferably, the lifting member 16 does not bear throughout its entire length against the inner surface of the standard formed by the stampings 13 and 14, as such an extended bearing surface would require a degree of accuracy in the manufacture of the jack which is in practice unnecessary. The outer diameter of the lifting member 16 is therefore somewhat less than the internal diameter of the standard. A bearing for the lifting member 16 is provided at the upper end of the standard by reducing the diameter of the standard at its top to form a neck 27 within which the lifting member 16 has a sliding fit. To prevent excessive lateral pressures on the screw 19 when the lifting member 16 is elevated, the nut 18 may be provided with a flange 28 of such a diameter as to

have a sliding fit within the cylindrical portion of the hollow standard.

For the purpose of preventing separation of the two stampings 13 and 14 at their upper ends, we 5 provide a collar 30 which closely surrounds the neck 27 of the standard and is secured in place thereon as by welding or by having a force fit on such neck. This collar 30 is not circumferentially continuous, but is interrupted at the slot 26, 10 as is clear from Fig. 4, to provide for upward movement of the step 25 beyond it.

It will be apparent that when the lifting member 16 is raised to a point such that the nut 18 will be above the lower end of the slot 26 that slot 15 will be uncovered and will provide a passage through which dirt or foreign matter could enter the interior of the housing. In the drawings, I have shown two different means for preventing the entrance of dirt or foreign matter in such 20 circumstances.

In the arrangement illustrated in Figs. 1 to 5 inclusive, this means takes the form of a sheet-metal shield 32 which partially, but not entirely, surrounds the lifting member 16. At the front 25 of the jack, this shield is formed to provide a trough 33 which receives the flanges 22 on the lifting member 16, as is clear from Figs. 2 and 3. At the upper end of the shield 32, there is formed on the trough 33 an outwardly projecting abutment 34 which is adapted to engage the bottom of the slot 26 and thereby to limit downward movement of the shield in the standard.

In order to accommodate the shield 32 between the lifting member and the interior wall of the 30 hollow standard, the stampings 13 and 14 are shaped to provide for the inner surface of the standard's portions having different radii of curvature. Near the back of the standard, as is clear from Fig. 3, the radius of curvature of the inner 35 face of the standard is substantially equal to the radius of the flange 28 on the nut 18; but at the sides and front of the standard this radius is greater in order to permit the presence of the shield 32.

45 At the lower end of the lifting member 16, there is provided on one or both of the flanges 22 a forwardly extending projection 36 which is adapted to engage an in-turned lip 35 at the upper end of the shield 32 as the lifting member 16 moves 50 upwardly. This is best understood from the showing of Fig. 1.

With the jack fully collapsed, as illustrated in the drawings, the shield 32 hangs down within the lower portion of the vertical standard, the 55 abutment 34 resting on the bottom of the slot 26. As the gear 20 is rotated by operation of the pinion 15 to raise the lifting member 16, the shield 32 will remain in the position illustrated until upward movement of the lifting member 16 has 60 progressed to such an extent that the projection 36 engages the lip 35 at the upper end of the shield. Upon continued upward movement of the lifting member 16, the shield 32 moves upwardly by reason of the engagement between the projection 36 and the lip 35 and prevents the slot 26 65 from becoming uncovered.

A slightly different means for preventing uncovering of the slot 26 is illustrated in Figs. 7, 8, and 9. Here, the stampings 13 and 14 are formed 70 so that the hollow standard is of substantially uniform dimensions along different diameters, as is clear from Fig. 9. At the lower end of the lifting member 16 there is mounted a member 40 of T-shaped cross-section, and disposed at the front 75 edges of the flanges 22 is a shield 41 formed of

sheet-metal of channel cross-section, the edges of the channel flanges being bent inwardly of the shield to engage behind the flanges of the member 40. The shield 41 is formed at its upper end to provide an out-turned abutment 34 and an in-turned lip 35 analogous in shape and purpose to the correspondingly numbered parts of the shield 32.

The shield 41 functions in substantially the same way as does the shield 32. When the lower end of the lifting member 16 remains below the bottom of the slot 26, the shield 41 occupies the position illustrated in Fig. 7, hanging from the abutment 34. Upon extended upward movement of the lifting member 16, however, the member 40 engages the lip 35; and thereafter, the shield 41 and the lifting member 16 move upwardly together, the shield 41 serving to prevent the entrance of foreign matter through the slot 26 into the interior of the housing.

95 The nut 24 is preferably butt-welded to the lower end of the sliding member 16. To eliminate the necessity for removing the "flash" which forms as the result of such butt-welding, the upper end of the nut 24 may be counterbored to a 100 diameter somewhat larger than the outer diameter of the lifting member 16, so that when the lifting member 16 is in place in such counterbore an annular space is provided around it. The flash formed during the butt-welding occupies 105 this annular space, and need not be removed.

Proper meshing relation of the pinion 15 and gear 20 is conveniently secured by provisions in the housing. To this end, the base 12 may be formed beneath the pinion 15 with an upwardly 110 projecting boss 45 the upper surface is at such a height as to engage the lower face of the gear 20 and prevent it from receding downwardly from engagement with the pinion 15. To limit upward movement of the gear 20 in the housing, the 115 stampings 13 and 14 are provided with internally projecting indentations 46 which, as is clear from Fig. 6, overlie the top of the gear 20. The boss 45 and the indentations 46, therefore, serve to maintain the pinion 15 and gear 20 in proper 120 meshing relation.

We claim as our invention:—

1. A screw jack, comprising a housing having a base and hollow vertical standard both formed of sheet-metal, a screw disposed vertically within said standard, a thrust-bearing acting between said screw and said base, a lifting member vertically slidable in said housing and having screw-threads co-operating with those of said screw, a gear mounted on the lower end of said screw for rotation therewith, and a pinion mounted in said housing above and in position to mesh with said gear, said base and standard being provided with indentations extending inwardly of said housing and positioned to engage opposite faces of 130 said gear to maintain it in proper meshing relation with said pinion.

2. A screw jack, comprising a housing having a base and hollow vertical standard, a screw disposed vertically within said standard, a thrust-bearing acting between said screw and said base, a lifting member vertically slidable in said housing and having screw-threads co-operating with those of said screw, a gear mounted on the lower end of said screw for rotation therewith, and a 140 pinion mounted in said housing above and in position to mesh with said gear, said base being formed of sheet-metal and provided with an upwardly extending indentation located under said pinion in position to engage the lower face of 145

said gear beneath the point of its engagement with said pinion in order to prevent its separation from said pinion.

3. A screw jack, comprising a housing having a base and a hollow vertical standard, a screw disposed vertically within said standard, a thrust-bearing acting between said screw and said base, a lifting member vertically slidable in said housing and having screw-threads co-operating with those of said screw, a gear mounted on the lower end of said screw for rotation therewith, and a pinion mounted in said housing above and in position to mesh with said gear, said base being provided on its upper face with a boss located under said pinion in position to engage the lower face of said gear beneath the point of its engagement with said pinion in order to prevent its separation from said pinion.

4. A jack, comprising a housing having a hollow vertical standard, a lifting member slidable within said housing, means for moving said lifting member, said standard having a longitudinal slot in its wall and said lifting member being provided with a lifting step projecting outwardly through said slot, and a shield adapted to cover said slot, said shield being slidably mounted in said housing and having a lost-motion connection with said lifting member.

5. A jack, comprising a housing having a hollow vertical standard, a lifting member slidable within said housing, means for moving said lifting member, said standard having a longitudinal slot in its wall, said slot extending downwardly from the upper end of said standard to a point intermediate the length of the standard, said lifting member having a longitudinal flange disposed in said slot, said lifting member having also a step located in the plane of said flange and projecting outwardly through said slot, and a shield adapted to cover said slot, said shield and lifting member having co-operating provisions causing the shield to move upwardly to close said slot when the lifting member moves upwardly to or above a point where the lower end of said flange is above the lower end of said slot.

6. A jack, comprising a housing having a hollow vertical standard, a lifting member slidable within said housing, means for effecting longitudinal adjustment of said lifting member, said standard being formed of two generally similar sheet-metal stampings the longitudinal edges of which are out-bent to form abutting flanges, one flange of each pair of abutting flanges being wider than its associated flange and being folded thereover to secure the two stampings together, the adjacent edges of said two stampings at one side of said standard being cut away to provide a slot extending downwardly from the upper end of the standard, a reinforcing member partially surrounding said standard near the upper end thereof, and a step on said lifting member extending outwardly through said slot.

7. A jack, comprising a housing having a hollow vertical standard, a lifting member slidable within said housing, means for effecting longitudinal adjustment of said lifting member,

said standard being formed of two generally similar sheet-metal stampings the longitudinal edges of which are out-bent to form abutting flanges, one flange of each pair of abutting flanges being wider than its associated flange and being folded thereover to secure the two stampings together, the adjacent edges of said two stampings at one side of said standard being cut away to provide a slot extending downwardly from the upper end of the standard, and a step on said lifting member extending outwardly through said slot.

8. A screw jack, comprising a housing having a base and a hollow vertical standard, a screw disposed vertically within said standard, a lifting member vertically slidable in said housing, said lifting member being formed of a piece of sheet-metal bent into tubular cross-section, at least one of the longitudinal edges of said lifting member being out-bent to provide a longitudinal flange, said standard being provided with an inwardly opening longitudinal groove in which said flange is received, and a nut secured to said lifting member and co-operating with said screw.

9. A jack as set forth in claim 8 with the addition that said standard is provided with a slot in the plane of said groove, a portion of the flange on said lifting member extending outwardly through said slot to form a step.

10. A jack, comprising a housing having a hollow vertical standard, a lifting member slidable within said housing, means for moving said lifting member, said standard having a longitudinal slot in its wall, said slot formed of sheet-metal bent into tubular cross-section, a portion of one of the longitudinal edges of said sheet-metal forming said lifting member being bent to extend radially outward through said slot and form a step.

11. A screw jack, comprising a housing having a base and a hollow vertical standard, a screw disposed vertically within said standard, a lifting member vertically slidable in said housing and having screw-threads co-operating with those of said screw, a gear mounted on the lower end of said screw for rotation therewith, and a pinion mounted in said housing above and in position to mesh with said gear, said screw being provided in its lower end with an axial recess, said base having a centrally disposed convex upward projection adapted to be received in such recess and to form with the wall thereof a thrust bearing, said base also being provided with an upwardly extending boss located under said pinion in position to engage the lower face of said gear beneath its point of engagement with said pinion in order to prevent its separation from said pinion.

12. A screw jack as set forth in claim 11 with the addition that said base is of sheet-metal, said boss being formed by an indentation in said base, and said projection being formed by a separate member secured to said base.
